SURFACE CLEANING APPARATUS

CROSS-REFERENCE TO RELATED
APPLICATIONS

This application is a continuation of U.S. patent application Ser. No. 16/184,650, filed Nov. 8, 2018, which issued as U.S. Pat. No. 11,206,960 on Dec. 28, 2021 and claims priority to U.S. Provisional Patent Application No. 62/585,108 filed on Nov. 13, 2017, the entire contents all of which are incorporated herein by reference.

BACKGROUND

The present invention relates to surface cleaning apparatus, and more particularly to brushrolls for surface cleaning apparatus. Surface cleaning apparatus use brushrolls to agitate a surface to be cleaned. In some surface cleaning apparatus, such as floor and carpet cleaners, the brushroll is located near the suction inlet. The brushroll agitates debris that is attached to or embedded in the surface being cleaned, which allows the suction source to draw the debris through the suction inlet.

SUMMARY

In one embodiment, a surface cleaning apparatus includes a brushroll that rotates about an axis. The brushroll defines a cylindrical portion and the axis extending centrally through the cylindrical portion. The brushroll further includes a rib that extends in a direction away from the axis. The rib includes a face extending along a line that is collinear with a secant through the cylindrical portion and a brush member extends from the face.

In another embodiment, a surface cleaning apparatus includes a brushroll that rotates about an axis. The brushroll includes a body, a rib extending outwardly from the body, and the rib having a face that forms an angle in the range of 60-120 degrees with respect to the body. The brushroll further includes a brush member extending outwardly the face and the brush member forms an angle in the range of 70-110 degrees with respect to the face.

In another embodiment, a surface cleaning apparatus includes a brushroll including a body having a cylindrical portion, a plurality of ribs extending outwardly from the cylindrical portion, and each rib having a face that contacts the cylindrical portion at a contact edge. The brushroll further includes a plurality of bristles extending from each face, at least a portion of each bristle being parallel, plus or minus 20 degrees, to at least one tangent to the cylindrical portion at the contact edge.

In another embodiment, a surface cleaning apparatus includes a brushroll that rotates about an axis. The brushroll includes a body and a plurality of ribs that extend outwardly from the body and helically along and around the axis. The brushroll further includes a plurality of bristles extend from a trailing face of each of the plurality of ribs.

Other features and aspects of the invention will become apparent by consideration of the following detailed description and accompanying drawings.

Before any embodiments of the invention are explained in detail, it is to be understood that the invention is not limited in its application to the details of construction and the arrangement of components set forth in the following description or illustrated in the following drawings. The invention is capable of other embodiments and of being practiced or of being carried out in various ways. Also, it is

to be understood that the phraseology and terminology used herein is for the purpose of description and should not be regarded as limiting.

5 BRIEF DESCRIPTION OF THE DRAWINGS

FIG. 1 is a perspective view of a surface cleaning apparatus.

10 FIG. 2 is an enlarged perspective view of the surface cleaning apparatus of FIG. 1.

FIG. 3 is a perspective view of a brushroll of the surface cleaning apparatus of FIG. 1.

15 FIG. 4 is a perspective view of a brushroll of the surface cleaning apparatus of FIG. 1 with a plurality of brush members removed.

FIG. 5 is a side view of a brushroll of the surface cleaning apparatus of FIG. 1.

20 FIG. 6 is a perspective view of another embodiment of a brushroll for use with the surface cleaning apparatus of FIG. 1.

FIG. 7 is a perspective view the brushroll of FIG. 6 with a plurality of bristle elements removed.

FIG. 8 is a side view of the brushroll of FIG. 6.

25 FIG. 9 illustrates perspective views of a brushroll according to another embodiment.

FIG. 10 is an exploded view of the brushroll of FIG. 9.

FIG. 11 is an exploded view of a brushroll according to another embodiment.

30 FIG. 12 illustrates perspective views of a brushroll according to another embodiment.

FIG. 13 is a perspective view of a brushroll according to another embodiment.

FIG. 14 is an exploded view of the brushroll of FIG. 13.

35 FIG. 15A is a side view of a brushroll of the surface cleaning device of FIG. 1 interacting with a floor.

FIG. 15B is a side view of a brushroll of the surface cleaning device of FIG. 1 interacting with a floor.

DETAILED DESCRIPTION

40 A surface cleaning apparatus 10 shown in FIGS. 1 and 2 includes a brushroll 12 operable to act on a surface to be cleaned. Although the illustrated surface cleaning apparatus 10 is a carpet extractor, in other embodiments the surface cleaning apparatus could include any type of surface cleaning apparatus that uses a brushroll. For example, an upright-style vacuum cleaner, a canister-style-vacuum cleaner, a power sweeper, a hard floor cleaner and the like. The surface cleaning apparatus 10 includes a suction source 14, a dirt separator 16 (a wet recovery tank in the illustrated embodiment), and a suction nozzle 18. The suction source 14 draws debris through the suction nozzle 18 and the debris is stored in the separator 16.

45 Referring to FIGS. 3-5, the brushroll 12 includes a brushroll body and one or more brush members 40. The brushroll 12 rotates about an axis 20 in operation. As illustrated in FIG. 5, a schematic cylindrical portion 22 having a cylindrical portion diameter 36 extends around the axis 20. The schematic cylindrical portion 22 may have a circular cross section or may be any other shape desired for the brushroll. The axis 20 extends centrally through the cylindrical portion 22. The brushroll 12 further includes ribs 24A-24F extending from the cylindrical portion 22 in a direction away from the axis 20. An outer extent of the ribs 50 60 form a brushroll body outer diameter 38. The brushroll embodiment illustrated in FIG. 4 includes six ribs, 24A-24F, whereas the brushroll embodiment illustrated in FIG. 7

includes four ribs. However, in other embodiments, the brushroll may include one, two, three, or more ribs. As the brushroll 12 rotates about the axis 20 in operation, each of the ribs 24A-24F have a trailing portion from which the brush members 40 extend, and a leading portion opposite the trailing portion.

The ribs 24A-24F are generally the same and therefore only one of the ribs 24A will be explained in detail. The rib 24A extends in a direction away from the axis 20 and the cylindrical portion 22 to the brushroll body outer diameter 38 forming a rib height. In one embodiment, the cylindrical portion diameter 36 is between about 45% and 80% of the brushroll body outer diameter 38. In another embodiment, the cylindrical portion diameter 36 is between about 60% and 75% of the brushroll body outer diameter 38. Referring to FIG. 5, the rib 24A includes a rib face 26 on the trailing portion of the rib 24A extending along a line 28 that is collinear with a secant 30 through the cylindrical portion 22. Stated another way, a secant 30 of a cross-section through the cylindrical portion 22 aligns with the rib face 26 of the trailing portion of the rib 24A. In the illustrated embodiment, the secant 30 is offset from the axis 20. The rib face 26 intersects the cylindrical portion 22 at a contact edge 34. The rib face 26 is also at an angle 32 with respect to the cylindrical portion 22. Specifically, the angle 32 is measured between the rib face 26 and a tangent 50 of the cylindrical portion 22 at the contact edge 34. In one embodiment the angle 32 is in a range from 60 degrees to 120 degrees. In another embodiment, the angle 32 is in a range from 80 degrees to 100 degrees. In the illustrated embodiment, the rib 24A extends helically along and around the axis 20.

Referring to FIGS. 5 and 8, the brush members 40 extend from the face 26 of the rib 24A along a longitudinal axis 48 of the brush member 40. An angle 42 is defined between the longitudinal axis 48 and the line 28. In one embodiment, the angle 42 is in a range from 70 degrees to 110 degrees. In other embodiment, the angle 42 is in a range from about 80 degrees to 100 degrees. The brush members 40 extend from the face 26 a length 44 such that a portion 46 of the length 44 of the brush members 40 are drawn along the surface to be cleaned as the brushroll 10 rotates about the axis 20. In one embodiment, the length 44 is greater than 0.5 times the cylindrical portion diameter 36. In one embodiment, the length 44 is greater than 0.65 times the cylindrical portion diameter 36. In yet another embodiment, the length is between 0.7 and 1.5 times the cylindrical portion diameter 36. The configuration of the face 26 and length 44, described above, allows the brush members 40 to be dragged along the surface being cleaned. Also, in the illustrated embodiment, a portion 56 of the brush member 40 adjacent the face 26 is parallel, plus or minus 20 degrees, to the tangent 50 of the cylindrical portion at the contact edge 34, as represented by longitudinal axis 48 in FIG. 5.

FIGS. 15A and 15B illustrate the interaction of the brush members 40 with a floor 61. For a given diameter 67 of brushroll 12, an offset rib face 63 provides for a longer filament of the brush members 40, which in turn provides an improved sweeping action. As shown in FIG. 15A, the brush members 40 engage with the floor 61 when the rib face 63 is offset further from a vertical plane 65 than a traditional brushroll. Therefore, the brush members 40 sweep a relatively large distance or angle along the floor 61. For example, as shown in FIG. 15A, initially a brush member 40 first contacts the floor 61 at an angle 69 of rotation of the brushroll 12 that is 40 degrees relative to the vertical plane 65. The same brush member 40 continues to contact the floor 61 until the brushroll 12 rotates to an angle 71 measured

from the vertical plane 65 that is 100 degrees in the illustrated embodiment. Therefore, the brush member 40 contacts the floor 61 for about 60 degrees of rotation of the brushroll 12. In other embodiments, the brush member 40 contacts the floor 61 between 40 degrees and 75 degrees of rotation of the brushroll 12. In another embodiment, the brush member 40 contacts the floor 61 between 50 degrees and 65 degrees of rotation of the brushroll 12. In yet another alternative, the brush member 40 contacts the floor 61 for more than 50 degrees of rotation of the brushroll 12.

In the illustrated embodiment, the brush members 40 include polymer bristles. In other embodiments, other suitable type of brush members may be used, such as fiber or rubber bristles, cloth strips or pads, beater bars, wipers, bristle strips, microfiber, and the like.

The brushroll body may be formed as a unitary structure, such as molded, machined, formed, cast, or otherwise formed as a one-piece body, or may be formed from two or more separate segments 54 (FIG. 4) that are attached together to form the brushroll body in a modular assembly. In one embodiment, the brushroll body is formed by two or more modular segments 154A-C assembled in axial alignment such as illustrated in FIG. 10. Whether a unitary or modular brushroll body, the ribs may be formed in segments 54 rotated or indexed slightly with respect to the adjacent segment 54 to create a stepped or segmented helical shape of the ribs 24A-24F as illustrated by the embodiment in FIGS. 3-5. Alternatively, whether unitary or modular, the ribs may form a continuous rib along the brushroll body as illustrated by the embodiment in FIGS. 6-8.

The brushroll body may be formed as a modular assembly with a plurality of segments 154A-154D such as the embodiment shown in FIGS. 9-14. This modular design allows for any suitable number of segments 154A-154D to be combined. This can provide for many different length brushrolls, color patterns, and pulley 155 locations. In the embodiment shown in FIG. 10, the modular segments 154A-154D include a projection 156 that is received in a corresponding aperture to couple the segments 154A-154D and optional pulley 155 for co-rotation in axial alignment. The projection 156 may be gear-shaped, square, keyed, polygonal, cylindrical, or any other shaped projection. The shape of the projection may be indexable in the corresponding aperture. Stated another way, the shape of the projection may fit into the aperture in two or more orientations to allow the segments 154 to be indexed or rotated a desired amount relative to the adjacent segment. The segments 154A-154D and optional pulley 155 can be fastened together by insert molding, press fitting, welding, gluing, bolts, screws, collar flanges, latches, and the like. The modular segments optionally may include tabs, keys, or other features such as shown in FIG. 11 in addition to the projection 156 that couple with corresponding features on an adjacent segment to provide a keyed or fitted orientation to aid in assembly of the segments in a desired arrangement, and may provide resistance to relative rotation between modular segments.

In one embodiment shown in FIG. 12, one or more of the modular segments include different types and configurations of brush members 40. Alternatively or additionally, brush members such as beater bars, wipers, bristle strips, cloth strips, microfiber, or other brush members may be installed over or between or in the form of segments. In the embodiment shown in FIGS. 13 and 14, a segment includes beater bar members positioned to overlap adjacent segments providing multiple interactions in the same area.

Various features of the invention are set forth in the following claims.

What is claimed is:

1. A surface cleaning apparatus comprising:
a brushroll including
  - a body having a cylindrical portion;
  - a plurality of ribs extending outwardly from the cylindrical portion, each of the plurality of ribs having a planar face extending along a line that intersects the cylindrical portion and the planar face contacts the cylindrical portion at a contact edge; and a plurality of polymer bristles extending from each planar face having a length extending, adjacent the planar face, being parallel, plus or minus 20 degrees, to at least one tangent to the cylindrical portion at the contact edge.
2. The surface cleaning apparatus of claim 1, wherein each of the plurality of ribs extends to an outer diameter, and wherein the plurality of polymer bristles extend radially outside the outer diameter.
3. The surface cleaning apparatus of claim 2, wherein the cylindrical portion has a cylindrical portion diameter which is more than 50% of the outer diameter.
4. The surface cleaning apparatus of claim 1, wherein the brushroll is configured to rotate about an axis in a rotation direction.
5. The surface cleaning apparatus of claim 4, wherein the planar face is a trailing face and the plurality of polymer bristles extend from the trailing face in a direction opposite the rotation direction.
6. The surface cleaning apparatus of claim 5, wherein the plurality of polymer bristles extends from the trailing face such that a portion of the length of the polymer bristles is drawn along a surface to be cleaned as the brushroll rotates about the axis.
7. The surface cleaning apparatus of claim 1, wherein each of the plurality of ribs extends helically along and around the cylindrical portion.
8. The surface cleaning apparatus of claim 1, further comprising
  - a dirt separator;
  - a suction nozzle;
  - a suction source operable to draw debris through the suction nozzle and into the separator;
 wherein the plurality of polymer bristles form a brush member that has a longitudinal axis that extends through the trailing face,
 wherein each of the plurality of ribs extends to an outer diameter, and wherein the plurality of polymer bristles extend radially outside the outer diameter,
 wherein the cylindrical portion has a cylindrical portion diameter which is more than 50% of the outer diameter,
 wherein the brushroll is configured to rotate about an axis in a rotation direction,
 wherein the planar face is a trailing face and the plurality of polymer bristles extend from the trailing face in a direction opposite the rotation direction, wherein the plurality of polymer bristles extends from the trailing face such that a portion of the length of the polymer bristles is drawn along a surface to be cleaned as the brushroll rotates about the axis.

9. A surface cleaning apparatus comprising:
a brushroll that rotates about an axis, the brushroll including:
  - a body, and
  - a plurality of ribs that extend outwardly from the body and helically along and around the axis,
 wherein a plurality of polymer bristles form a brush member wherein the brush member extends from a planar trailing face of each of the plurality of ribs, wherein the body includes a cylindrical portion, and wherein the planar trailing face extends along a line that is collinear with a secant through the cylindrical portion, and wherein the brush member has a longitudinal axis that extends through the planar trailing face.
10. The surface cleaning apparatus of claim 9, wherein the body is formed by two or more modular segments assembled in axial alignment.
11. The surface cleaning apparatus of claim 10, wherein the planar trailing face forms an angle in the range of 60-120 degrees with respect to the body.
12. The surface cleaning apparatus of claim 9, further comprising, a suction source;
  - a dirt separator in fluid communication with the suction source; and
  - a suction nozzle in fluid communication with the dirt separator and the suction source.
13. The surface cleaning apparatus of claim 12, wherein the brushroll is positioned in the suction nozzle adjacent a surface to be cleaned.
14. A surface cleaning apparatus comprising:
a brushroll that rotates about an axis, the brushroll including:
  - a body with an outer profile having an outer diameter;
  - a planar trailing face extending along a line that is collinear with a secant through the outer profile;
  - wherein the trailing face is positioned on a rib extending outwardly from the body; and wherein a plurality of polymer bristles form a brush member extending from the planar trailing face, wherein the brush member has a longitudinal axis that extends through the planar trailing face.
15. The surface cleaning apparatus of claim 14, wherein the rib extends helically along and around the axis.
16. The surface cleaning apparatus of claim 14, wherein the trailing face forms an angle in the range of 60-120 degrees with respect to the body.
17. The surface cleaning apparatus of claim 14, wherein the brushroll is positioned in the surface cleaning apparatus such that the brush member sweeps along a surface when the brushroll is rotated.
18. The surface cleaning apparatus of claim 9, wherein an angle is defined between the longitudinal axis of the brush member and the line, and wherein the angle is in a range from 70 degrees to 110 degrees.
19. The surface cleaning apparatus of claim 14, wherein an angle is defined between the longitudinal axis of the brush member and the line, and wherein the angle is in a range from 70 degrees to 110 degrees.
